William Johnson New York City
Letters Patent

The Schedule referred to in these Letters Patent and making
part of the same containing a description in the words of the said
William Johnson himself of his improvement to mills for
grinding Grain. Paints. Dye-stuffs &c called the eccentric
brick Mill or grinder

To all to whom these presents shall come.

Be it known that I William Johnson of the City of New York
in the County and State of New York have invented a new and
useful improvement in Mills for grinding Grain. Paints. Dye-stuffs &c
called the eccentric brick Mill or grinder and that
the following is a full and exact description of the construction
and operation of the said Mill as improved by me. The bed stone
or stone properly the driver since it conveys motion to what is usually
called the runner in ordinary Mills is made in the usual way
of the same materials of those in common use. being either of stone
or metal. and of such diameter as shall best suit the work
to be performed and the power to be employed. The driver consists
simply of a number of raised points resembling the surface of a rasp
which I prefer for grinding Grains &c. but for grinding Dye-stuffs
&c. of a spiral groove or furrow commencing at the center and running
to the circumference of the stone. The eccentricity of which points
must be small so that the surface may be well covered in either
case. a number of straight short furrows are cut radiating oblique
by bush from the center of the stone which furrows must be of
a length not to pass out from under the runner hereafter men-
tioned and become shallower as they proceed from the center.
their object being solely to facilitate the passing of the grain &c.
to the grinding surface. The driver is made permanently

fast upon the propelling end of a horizontal shaft which has a double bearing and runs in appropriate boxes so that the motion of the driver may be steady and true. The shaft receiving its motion from the moving power by a strap or cog gearing as may be preferred. It is also intended to turn it smaller at its bearings so as to admit of a lateral movement by which the distance of the driver from the runner can be regulated and the mill be made to grind coarse or fine. This movement may be effected by a tempered screw spring, weightless lever, or by any of the means used for similar purposes. The top stone or runner is made of the same material as the driver. The dress being similar, except that it is recessed it has a circular opening or eye at the centre which I have found in practice should be about 2 inches in diameter for grain &c or about 4 for large stuff &c when the diameter of the driver is 2½ feet, but this must of course be varied to suit circumstance. From the back of this runner which is hollowed out so as to bring the attachment as near the face of the stone as may be for strength. A short hollow shaft issues the bore of which forming a continuation of the eye of the stone and which when metal is used may be cast solid with the runner through which bone the substance to be ground is fed to the grinding surface, being enlarged at the outer extremity so as to admit the grain &c more freely or receive the foot of the feed hopper hereafter mentioned. A neck or wrist is also turned in the shaft (on which may also be formed by a screw ring) at the end extending from the back of the runner near this end is which projects with a square shoulder beyond the bearing of the shaft which latter is a cylindrical box of suitable material that projects into the cavity of the back of the runner so that the neck or wrist of the shaft being slightly diminished (wards its outer extremity) the bearing is chiefly upon the inner portion of the box close to the face of the runner as practicable. This arrangement is intended to admit of a slight vibration to the runner when grinding that it may accommodate

to fit to the irregularities that may take place in the feeding, between the grinding surfaces. When the bearing of the runner is raised above that of the driver so as to bring the lower edge of the eye on a level or a short distance above the centre of the driver, making thereby the eccentricity equal to the diameter of the eye, and the difference of the diameters of the stones being made equal to the eccentricity, the upper part of this circumference when together coincide.

The feed hopper which is of a trumpet shape and receives the grain to come from the shoe of an ordinary hopper into which it is first thrown is supported in an oblique position so as to afford an easy descent to the grain to by a short bracket or arm which rises from the upright bearing of the runner shaft to which it is attached, its foot is diminished so as to enter the enlarged end of said shaft and fit it neatly without friction, it is prolonged by a small square bar or finger which is attached to the inner surface of the lower end of said foot and winds spirally along the cavity of the shaft until it nearly reaches the face of the runner. The office of this finger being to assist the feeding and to prevent chocking from adhesion to the sides - particularly when grinding grain. The stones are surrounded with with a case of ordinary construction with a proper discharging outlet two tubes being introduced opposite the extremities of the horizontal diameter of the driver for the purpose of keeping up a constant circulation of fresh air which by the peculiar operation of the grinding surfaces is drawn in at one side and discharged at the other.

Operation. - The substance to be ground being placed in the hopper and the mill set in revolution by the combined motion of the spiral finger, and the driver and runner it is fed to the grinding surfaces which reduce it rapidly to the degree of fineness for which the mill is set. Although I have only described the mill as operating with the grinding surfaces in a vertical position, I also intend to operate it horizontally by making a suitable alteration in the lower bearing or step of the driving shaft and

dispensing with the feed hopper only retaining the upper finger & this position for grinding, some substances will be found to answer best. Now I do not claim the principle of placing the driver and runner eccentric to each other, but what I do claim as new & as my invention for which I ask a letter patent is the following
shape of the runner attached and supported as herein described and the spiral finger and feed hopper by the joint operation of all which together with the grinding surfaces of the runner and driver, the runner is properly sustained and the feeding effected. I also claim the drifts of the stones as set forth in the plan of moving the bed stone to regulate the mill instead of the upper stone or runner — On testimony that the foregoing is a true specification of my said improvement I do now witness unto before you and this 16th day of June 1835
